UNITED STATES PATENT OFFICE.

JOSEPH C. DONNELLY, OF BARBERTON, OHIO, ASSIGNOR TO THE DIAMOND MATCH COMPANY, OF CHICAGO, ILLINOIS, A CORPORATION OF ILLINOIS.

BLOCK-FEEDING MECHANISM FOR MATCH-MACHINES.

1,168,864.

Specification of Letters Patent. Patented Jan. 18, 1916.

Application filed April 28, 1914. Serial No. 834,906.

To all whom it may concern:

Be it known that I, JOSEPH C. DONNELLY, a citizen of the United States, and resident of Barberton, in the county of Summit and 5 State of Ohio, have invented certain new and useful Improvements in Block-Feeding Mechanism for Match-Machines, of which the following is a specification.

This invention relates to block-feeding 10 mechanism for match machines, the object of the invention being to provide for the positive feeding of the blocks in a direct course along the trough, irrespective of the condition, whether even or uneven, of the 15 adjacent ends of succeeding blocks.

Accordingly my invention consists, primarily, in the combination with a feeding trough of screw-mechanism extending longitudinally thereof and positioned to engage 20 the opposing surfaces of the blocks and act not only to advance the blocks positively along the trough but also to maintain them squarely against the inner longitudinal guide wall of the trough, and this without 25 the intervention of springs or spring-actuated devices.

The invention also comprises novel features of construction and combinations of parts which will be hereinafter fully described and claimed.

In the drawings—Figure 1 is a plan of block-feeding mechanism embodying a preferred form of my invention, the cover-plate of the feed-trough, including the bearings 35 for the feed-screws, being removed. Fig. 2 is a longitudinal vertical section, as on the line 2—2 of Fig. 1. Fig. 3 is a transverse vertical section, partly in elevation, as on the line 3—3 of Fig. 2. Fig. 4 is a partial 40 side elevation of the trough, showing the gearing and pawl and ratchet mechanism for actuating the feed screws.

10 designates a supporting frame, and 11 a block-feed trough formed or arranged thereon obliquely to the row of splint cutters, as usual. This trough is adapted to receive the blocks 12 and guide them to the path of the cutters. In the present instance 45 a double feed-trough is illustrated, whereby two parallel rows of blocks are directed to the cutters, but, of course, a single feed-trough may be employed if desired.

13 designates parallel feed-screws which 50 are arranged in pairs longitudinally of the top and bottom of the respective sections of

the trough in such position that the threads of the screws engage the opposing surfaces of the blocks and not only intermittently impel them toward the cutters but maintain the blocks in contact longitudinally with the 60 adjacent guide walls 14 of the sections; thereby preventing lateral play of the blocks and insuring their positive advance to the cutters. Each pair of feed screws is journaled in suitable bearings in the top and 65 bottom of the trough, the threads of the respective screws of each pair being oppositely-pitched and provisions being had whereby they are rotated in opposite directions to each other and at the same speed so 70 that their threads shall exert a uniform feeding action upon the opposing surfaces of the blocks and at the same time shall tend to thrust the blocks laterally against the adjacent guide wall. The forward or receiving 75 ends of the screws are tapered, as indicated at 15, to facilitate their engagement with the advancing ends of the blocks, and the threads of these tapered portions are preferably made somewhat heavier than the 80 threads of the main portions of the screws so as to indent the surfaces of the blocks and prepare them for engagement by the latter threads.

Any suitable means for intermittently rotating the feed screws may be employed. In the present instance the forward end of each of the screws is extended and a gear wheel 16 with oblique teeth is formed thereon. The gear wheels 16 of the upper feed screws mesh with a pair of appropriate gears 17 on a transversely disposed shaft 18 above the trough, and the gear wheels 16 of the lower feed screws mesh with a pair of similar gears 17 on a shaft 19 beneath the trough. The 90 ends of the shafts 18, 19 extend beyond one side of the trough and bear gear wheels which are included in an appropriate gear train actuated through suitable pawl-and-ratchet devices, as follows: 20 is a ratchet wheel mounted on a stud-shaft 21 supported in a suitably-disposed bracket 22, and 23 is a pawl which engages the teeth of the ratchet wheel. This pawl is pivoted to one 95 arm of a rock-frame 24 which is loosely hung on said shaft, the other arm of the frame being jointed to an operating rod 25 which is reciprocated by a cam element of the match machine.

Fast on the stud shaft 21 is a gear wheel 110

26 which meshes with a gear wheel 27 on a lower stud shaft 28 having its bearing in the bracket 22; and fast on the latter shaft is a gear wheel 29 which meshes with a gear 5 wheel 30 on the lower transverse shaft 19. On this shaft 19 is a gear wheel 31 which meshes with an idler gear 32 mounted to turn on a stud 33 borne by an adjustable supporting arm 34 on the side of the trough, 10 said idler gear meshing with a gear wheel 35 on the upper transverse shaft 18. By this construction it will be seen that during the oscillation of the pawl-bearing frame 24 the ratchet wheel 20, its shaft 21 and the 15 gear wheel 26 thereon are intermittently rotated, the wheel 26 transmitting motion through the gears 27, 29, 30 to the lower shaft 19, and the gear 31 on the latter transmitting motion through the idler gear 32 20 and the gear wheel 35 to the upper shaft 18. 36 is a suitably-located back-stop dog which 37 is a hand-wheel on the stud of the pawl 23, which hand wheel may be readily turned 25 by the attendant to disengage the pawl from the ratchet wheel when it is desired temporarily to stop the feeding-operation.

It is to be noted that as the screws of each 33 set grip the block from front to rear, there is no liability of upward tilting pressure on a forward block by the contiguous rearward block should the opposing ends of the blocks be uneven. Further, that as the 38 said screws with oppositely-pitched threads are rotating in opposite directions to each

other, and at the same speed throughout the length of the trough, the block is caused to move evenly forward and is held against the adjacent guide wall 14, which is preferably polished to provide a sliding surface. 40 Should it happen that a block in front is too small to be gripped by the screws it will be impelled by the opposing rearward block.

It is to be understood that my invention is not limited to the details of construction 45 herein shown and described as the structure may be modified without departing from the spirit of the invention.

I claim—

In block-feeding mechanism for match 50 machines, the combination with a block-feeding trough having a longitudinal side-guide for the contained blocks, of feed-screws extending adjacent to and longitudinally of the bottom and top respectively of 55 the trough, the threads of said screws being oppositely pitched, and means for rotating said screws in opposite directions to each other, whereby the threads of the said screws engage the opposing lower and upper 60 surfaces respectively of the blocks and impel the blocks along the trough and in lateral contact with the said side-guide.

Signed at Barberton in the county of Summit and State of Ohio this 23rd day of 65 April, A. D. 1914.

JOSEPH C. DONNELLY.
